Application July 12, 1940, Serial No. 345,099

43 Claims. (Cl. 12—33)

This invention relates to sole and shoe locating mechanisms for use in machines for applying pressure to shoe bottoms such as cement sole attaching machines.

Objects of the invention are to provide mechanism for insuring that the rear part of the sole comprising the shank portion and heel portion thereof is always positioned centrally on the pad of the pressure applying machine, that is, in alignment with the longitudinal median line of the pad while at the same time maintaining the proper angular relation between the longitudinal median lines of the sole forepart and the sole rear part respectively. This centralizing of the rear part of the sole on the pad is highly desirable, if not a necessary prerequisite, for the proper attachment of soles to shoe bottoms by cement because, by reason of it, the rear portion of the sole, particularly the shank portion thereof, is properly located in the depression normally formed in the pad to receive the shank portion of the sole. Adjustment of the forepart of the sole in alignment with the longitudinal center line of the pad, particularly in cases of soles with a pronounced "lateral swing" of their foreparts (angular disposition of sole forepart relatively to sole rear part), is apt to displace the rear part of the sole beyond the periphery of the pad.

In accordance with the invention, therefore, the illustrated pad box is provided with means for positioning the forepart of a sole at an angle relatively to the longitudinal median line of the pad and means for positioning the rear part of the sole centrally on the pad, the forepart positioning means being constructed and arranged for adjustment in accordance with the lateral swing of the sole and shoe operated on, such that the rear part of the sole will be properly disposed relatively to the forepart after the rear part has been positioned centrally on the pad.

Moreover, the illustrated apparatus is provided with shoe positioning means so associated with the sole positioning means that the shoe is automatically positioned in proper relation to the sole previously positioned on the pad.

These and other features of the invention, including certain novel arrangements and combinations of parts, will appear more fully from the following description when read in connection with the accompanying drawings and will be pointed out in the appended claims.

In the drawings,

Fig. 1 is a plan view of a pad box equipped with sole and shoe positioning mechanism embodying the present invention;

Fig. 2 is a detailed view in side elevation of part of the mechanism for positioning the foreparts of the sole and the shoe;

Fig. 3 is a detailed view, partly in section, of part of the mechanism for positioning the forepart of the sole, the section being taken along the line III—III of Fig. 1;

Fig. 4 is a sectional detailed view taken along the line IV—IV of Fig. 1;

Fig. 5 is a rear elevational view of the mechanism for positioning the rear parts of the sole and the shoe;

Fig. 6 is a sectional view of part of the mechanism shown in Fig. 5, the section being taken along the line VI—VI of Fig. 5;

Fig. 7 is a sectional view, the section being taken along the line VII—VII of Fig. 6;

Fig. 8 is a side elevational view of part of the mechanism for positioning the rear parts of the sole and the shoe;

Fig. 9 is a sectional detailed view of part of the mechanism shown in Fig. 8; and

Fig. 10 is a transverse sectional view of the shoe and the pad in the vicinity of the heel breast line, showing particularly the gages for positioning the rear part of the sole.

In Fig. 1 a shoe S and an outsole O are shown as relatively positioned by mechanism embodying the present invention as applied to a cement sole attaching machine of the type disclosed in United States Letters Patent No. 2,047,185, granted July 14, 1936, upon an application of Ballard et al., the pad being of the type disclosed in an application for Letters Patent of the United States, Serial No. 209,324, filed August 15, 1939, in the name of Royal G. Madan. It is to be understood that the present invention is not limited in its applicability and utility to a pad of the illustrated type, or to a cement sole attaching machine of the type disclosed in the above-mentioned Ballard patent.

The mechanism for locating the forepart of a sole on the pad, in such a position that the rear part of the sole can be positioned centrally on the pad without distortion of the sole, is illustrated in Figs. 1 to 4 of the drawings and comprises a fork-shaped toe end positioning member or gage 20 (Figs. 1 and 2) to which are pivotally secured two small positioning plates 24 and 26, the free edges of which rest by gravity against a cover 30 (Fig. 10) on a pad 31 (Fig. 3) contained in a box 32, this being substantially similar to the disclosure in an application for United States Letters Patent, Serial No. 286,600, filed July 26, 1939, in the name of Sidney J. Finn. The toe end gage

20 is supported on a slide 34 arranged for movement in the direction of the longitudinal medial line of the forepart of the sole. As in the construction of the above-mentioned Finn application, the gage carrying end of the slide 34 is arranged for a limited amount of movement perpendicularly to the pad cover 30 about a pivot stud (not shown).

The slide 34 is guided for its longitudinal movement in a carrier 40 (Fig. 1 and 2). The carrier 40 has on its under side a T-shaped guideway which is engaged by a guiding member in the form of a curved plate or segment 44 and is adjustable along the segment 44. The segment 44 is pivotally mounted on a screw 46 (Figs. 1 and 4) which is threaded into the pad box 32. The segment 44 is curved about a center located substantially at the intersection of the longitudinal median line *a* (Fig. 1) of the forepart of the sole with the longitudinal median line *b* of the rear part of the sole and, hence, the carrier 40 may be adjusted along the segment 44 about this intersection as a center, the adjustment being made for the sole gage to accommodate properly soles having different swings, that is, the longitudinal median lines of the foreparts and rear parts of which are disposed at different angles relatively to each other. For the purpose of enabling the sole and shoe locating mechanism of the present construction to accommodate soles having extreme swings, the segment 44 is arranged for adjustment about its fulcrum 46, a clamping screw 47 which engages one end of the segment 44 and normally clamps it against the pad box 32 serving to hold the segment in adjusted position. The carrier 40 is held in adjusted position on the segment 44 by a screw 48 threaded through a lug on the carrier 40 and engaging the side face of the segment 44. The segment is provided with a graduated scale, generally indicated at C, which serves to indicate the position of adjustment of the carrier 40. Similarly, the position of adjustment of the segment 44 about its fulcrum 46 is indicated by a scale A over which is movable an index finger pivotally secured to a fixed plate on which the scale A is provided and connected by a short link 49 to one end of the segment 44 (see Fig. 1). As illustrated in Fig. 1, the segment 44 carries a stop screw 50 which serves to limit the adjusting movement of the carrier 40 in one direction since the pad box is designed to operate only on right soles and shoes. It is to be understood that for operating upon left soles and shoes the arrangement of the parts, particularly the gages, is the mirror image of that shown in Fig. 1 of the drawings. The various adjustments mentioned above may be conveniently made in accordance with a chart to be described on which are plotted the proper positions of the various gages against different sizes, widths and styles of lasts.

As in the apparatus disclosed in the above-mentioned Finn application, the slide 34 is pivotally connected by means of a link 62 (Fig. 1) to a lever 66 pivoted between spaced depending brackets 72 (Fig. 2) on the carrier 40 and is operated through an intermediary spring mechanism by means of a rocker member 92 (Fig. 1) provided with a groove 90. The rocker member 92 is pivotally secured at both ends to fixed brackets by pins 94, the axes of the pins 94 being substantially in alignment with the pivot of the lever 66. On the side of the pad away from the operator (top side in Fig. 1) the rocker member 92 has an upwardly extending arm 96 (Fig. 1)

which is pivotally secured to one end of a link 100. The link 100 is pivotally secured at its other end to a lever 104 pivotally mounted at 106 on the pad box and actuated to operate the sole and shoe locating gages. A tension spring 108 (Fig. 1) connected at one end to the link 100 and at its other end to a pin 110 on the pad box assists in swinging the rocker member 92 in a clockwise direction, as viewed from the operator's side of the pad, so as to move the sole and shoe locating mechanism yielding into operative position when the lever 104 is actuated. The operation of the sole and shoe locating mechanism by the spring 108 and link 100 is quite similar to that disclosed in the above-mentioned Finn application.

To locate the forepart of the shoe with respect to the forepart of the sole already located by the gage 20, a fork-shaped gage 112 (Fig. 1) is provided. The gage 112 is adjustably connected at 114 to a slide 116 (Figs. 1 and 2) arranged on the slide 34 for movement in a direction parallel to the movement of the latter slide, the slide 116 being held in place on the slide 34 by a screw 118 passing through a slot in the slide 116 and threaded into the slide 34. To adjust the slide 116 relatively to the slide 34 so as to adjust the shoe end gage 112 relatively to the sole end gage 20, a screw 124 (Figs. 1 and 4) is provided the head of which engages a notch formed in the slide 34 and the stem of which is threaded through an upstanding lug on the slide 116. To indicate the amount of adjustment imparted to the slide 116, a plate 134 (Figs. 1 and 2) is attached by a screw to the slide 34. The plate is provided with a graduated scale D over which is movable an index finger 140 pivotally secured to the plate 134, and rotated by means of connections to the slide 116.

It is a purpose of this invention to locate the forepart of a sole in such a position on the pad that the rear part of the sole can be located centrally on the pad without distorting the sole. If the sole happens to be initially distorted, its shape is corrected by the same operation. In view of the fact that the inner side of the forepart of a sole extends in a substantially straight line for a considerable distance, this part of the sole is preferably used for gaging purposes, that is, for determining the position of the sole widthwise of the pad, and, consequently, the present construction is provided with sole side gaging means, about to be described, which is moved to a predetermined position on the pad in accordance with the selected position of adjustment of the sole end positioning mechanism and against which side gage the sole is moved by a sole engaging member or pusher, also to be described. A plate 150 (Fig. 1) is pivotally secured by a pin 152 to a plate 151 secured to the top face of the slide 34 at the side nearest the operator's position and is held in adjusted position about the pivot pin 152 by a clamping screw 154. The position of adjustment of the plate 150 is indicated on a graduated scale E provided on the plate 150 over which extends an index finger secured to the carrier 40 and relatively to which the plate 150 is adjusted.

The plate 150 serves as a cam means for actuating the above-mentioned side gage. To that end, the plate 150 is provided with a longitudinal slot 156 (Fig. 1) which is inclined relatively to the direction of movement of the slide 34 and which is engaged by a downwardly extending pin carried on one extremity of an arm 158 (Figs. 1

and 2) having a hub portion pivotally mounted on a vertical pin 160 secured to a plate 159 fixed on the pad box 32. Extending from the hub portion of the arm 158 is a gage carrying arm 161 to the forward end of which is pivotally secured a block 162 carrying the side gage 164, the gage 164 being adjustable by means of a screw 166 along a guideway provided in the top face of the block 162. The adjustment of the side gage 164 is indicated on a scale E (Fig. 1) on a plate secured to the block 162 over which plate is movable an index finger secured to the gage 164. Upon movement of the slide 34 toward the toe portion of the sole, the arms 158 and 161, due to the cam action of the slot 156 of the plate 150, which cam action may be varied by an adjustment of the plate 150 about its pivot 152, are swung in a counterclockwise direction, as viewed in Fig. 1, to move the gage 164 into its operative position. Moreover, on adjustment of the plate 150 about its pivot 152 the amount of angular movement imparted to the arms 158 and 161 is varied correspondingly and hence the operative position of the gage 164 is varied. The amount of inward movement imparted to the gage 164 as a result of the angular movement of the arms 158 and 161 depends also on the amount of movement of the slide 34 toward the toe portion of the sole which, in turn, is determined by the size of the sole.

In order to insure that the forepart of the sole is pushed against and held in contact with the gage 164, a sole contacting member or pusher engaging the side of the sole opposite from that acted upon by the gage 164 is provided. Rotatably mounted on the stem of the clamping screw 47, previously described as serving to hold the segment 44 in its position of adjustment, is the hub portion of a short link 170 (Figs. 1 and 3) to which is pivotally secured, by means of a horizontally extending pin 172, one end of an arm 174 carrying at its other end the abovementioned sole engaging member or pusher 176. A leaf spring 175 secured at its one end to the link 170 (Fig. 3) presses upon the arm 174 so as to hold the pusher 176 in engagement with the pad 31. The pusher 176 is mounted for adjustment along a longitudinally extending slot 178 (Fig. 1) provided in the free end of the arm 174.

For the purpose of actuating the pusher 176 the arm 174 is provided at its lower surface with a roll 180 extending into a slot 182 provided in a plate 184 guided for movement longitudinally of the pad by means of two screws 186 extending through a longitudinally extending slot 188 in the plate 184 and threaded into the pad box 32. As will be seen in Fig. 1, the major portion of the slot 182 extends at an angle relatively to the longitudinal direction of the pad and, hence, upon movement of the plate 184 toward the right of Fig. 1 the pusher 176 is moved inwardly into engagement with the edge face of the sole on the pad and after having engaged the sole the pusher 176 continues to move in the same direction so as to move the sole against the gage 164.

For the purpose of actuating the plate 184, it is connected by means of a link 190 (Fig. 1) to a lever 192 which is oscillated through the intermediary of a spring mechanism 194 by the previously-mentioned rocking member 92, this actuating mechanism being in substance similar to that disclosed in the above-mentioned Finn application.

For positioning the rear part of the sole centrally on the pad after the forepart of the sole

has been positioned on the pad by the above-described forepart positioning mechanism, the illustrated apparatus is provided with two gages 200, 204 which are adapted to move equally and oppositely and which engage the opposite sides of the shoe sole in the vicinity of the heel breast line, preferably somewhat in front of that line. One gage 200 is adjustably secured to an arm 202 and the other gage 204 is adjustably secured to an arm 206 which is similar to the arm 202. The arms 202 and 206 are each engaged by a spring 207 (Fig. 8) serving to hold the arms 202 and 206 in their lowermost positions so that upon inward movement of the arms 202 and 206 the gages 200, 204 may readily engage the edge faces of the opposite sides of the sole, as indicated in Fig. 10. The arm 202 is pivotally secured by means of a horizontal pin 208 to the upper portion of a shaft 210 rotatably mounted on a vertical slide presently to be described. Similarly, the arm 206 is pivotally secured by means of a pin 212 to the upper portion of a similarly mounted shaft 214. The shaft 210 (Fig. 6) is provided with a rearwardly extending arm 216 to which is pivotally secured a link 218. The shaft 214 also is provided with a rearwardly extending arm 220 to which is pivotally secured a link 222. The arms 216 and 220 are of equal length. The links 218 and 222 are also of equal length and their inner ends are joined by a pivot pin 224 (Figs. 5, 6 and 7). The pin 224 is guided for movement in the longitudinal direction of the pad in two parallel slots provided in two parallel guiding members 226 and 228 (Fig. 7) rigidly secured to the above-mentioned slide 229 (Figs. 5 and 6) which is mounted for vertical movement in a guideway provided in the pad box substantially as in the construction of the above-mentioned Finn application. The pin 224 is connected to a lever 232 by means of a double link member 230 interposed between the two guiding members 226, 228. The lever 232 is secured substantially midway of its length as 234 to a bracket 236 on the vertically movable slide 229. The lever 232 is connected by means of a universal joint 238 to a sleeve 240 which is loose on a rod 242 and which on movement of the rod 242 toward the right of Fig. 1 is engaged and moved in the same direction by a collar 241 secured on the rod so as to move the gages 200, 204 into engagement with the sole. In the normal position of rest of the machine the collar 241 is located at a predetermined distance from the left-hand end of the sleeve 240 (Fig. 1) so that on movement of the link 100 and rod 242 toward the right of Fig. 1 to actuate the gages the collar 241 is moved idly at first and as a result of this lost motion between collar 241 and sleeve 240 the sole and shoe forepart gages are actuated before the rear part gages. As will be seen in Figs. 1 and 6, the rod 242 is provided at its rear extremity with locknuts 244 which in the operative position of the gages are located at a certain distance from the rear end of the sleeve 240. Hence, upon initiation of the movement of the link 100 and rod 242 toward the left of Fig. 1 to withdraw the gages, no movement is initially imparted to the lever 232 and the gages 200 and 204, the latter members being retracted only after the nuts 244 have traversed the lost motion thus provided between the sleeve 240 and the nuts 244 and have contacted the rear end of the sleeve 240. The rod 242 is pivotally connected by means of the pivot pin 102 to the previously mentioned lever 104 which

also serves to actuate the forepart locating mechanism.

For locating the rear end of the shoe, the machine is provided with a V-shaped gage 248 (Figs. 1, 8 and 9) similar in construction and arrangement to the corresponding gage disclosed in the above-mentioned Finn application. The gage 248 has a longitudinally bored square stem 250 which is received between the vertical surfaces formed in a slide 252 which in turn is supported on a transversely movable slide 253. The stem 250 carries a transverse pin 256, the ends of which are fixed in the slide 252 (Figs. 5 and 9). Provided in the bore of the stem 250 between the pin 256 and a cotter pin is a compression spring 260 which tends to push the gage 248 yieldingly toward the shoe. The stem 250 is permitted a limited amount of movement in a vertical plane about the pin 256 and is normally held in an upwardly tilted position against a 20 262 (Fig. 5) by a leaf spring 263 (Fig. 9) secured to the slide 252.

To hold the slide 252 in operative position and prevent its rearward movement, a pair of pawls 270, 272 (Figs. 1 and 8) is provided, the pawls 25 being pivoted to the slide 252 and arranged to engage a rack bar 276 secured to the previously-mentioned transverse slide 253. The construction and arrangement of these parts is identical with that disclosed in the above-mentioned Finn application. As in the Finn application, the pawls are held in engagement with the rack bar 276 by a spring 286 (Fig. 8) and are adapted to be raised out of locking engagement with the rack bar 276 by means of a rearwardly extending projection 292 provided on a hand lever 294. The hand lever 294 is pivotally secured at its lower extremity to a short bifurcated arm 296 fixed to a pivot pin 298, a surface 300 of the arm being adapted to be engaged by the lower extremity of the hand lever 294 in a manner disclosed in the Finn application. Rigidly secured to the pivot pin 298 is a block 302 (Fig. 9) provided with a rearwardly extending projection the lower surface of which is engaged by a spring 304. The block 302 may be utilized for the attachment thereto of a blade-like member or tongue (not shown) that may be inserted between the rear end of a short outsole and the shoe bottom to prevent the formation of a cement bond at that location in case it is desired to attach to the shoe a heel of the type disclosed in United States Letters Patent No. 2,121,172, granted June 21, 1938, upon an application of Lovejoy, which heel is provided with a forwardly projecting lip that is inserted in the space between the outsole and the shoe bottom.

For the purpose of adjusting the slide 253 transversely of the pad, the vertically movable slide 220 is provided with a bracket 312 (Fig. 8) carrying a hand screw 310 threaded into a lug 311 on the transverse slide 253 (Fig. 5). Axial movement of the hand screw 310 is prevented by the interengagement of its head with the bracket 312 so that upon rotation of the screw 310 the slide 253 is adjusted in a horizontal direction transversely of the pad. The amount of this adjustment is indicated by means of a gage F (Fig. 1), it being understood that upon adjustment of the slide 253 the position of the shoe engaging fork-shaped gage 248 is varied with relation to the two breast gages 200 and 204.

The various gages A, B, C, D, E, F, referred to above, may be utilized in obtaining a quick and accurate adjustment of the positions of the vari-

ous gage mechanisms such that the forepart of a sole placed on the pad is positioned at an angle relatively to the longitudinal median line of the pad and that the rear part of the sole is positioned centrally on the pad without distortion of the sole. The shoe itself will be automatically positioned in accordance with the position of the sole. Upon occurrence of a change in the size or width or style of the soles it would be theoretically possible to make the necessary adjustments by properly positioning a templet sole corresponding in size, width and style to the soles about to be operated upon on the pad and changing the setting of all gages in accordance therewith. Since such an operation, however, would involve considerable work and delay, and since normally operators cannot be relied upon to make these adjustments, it is proposed to facilitate the setting of the various gages by means of a chart on which have been plotted the proper settings of the various gages A to F against lasts of various sizes, widths, and styles and designed to accommodate heels of various heights. Such a chart may be substantially as follows:

Gages

Last No.	A	B	C	D	E	F	Size
603 14/8 heel	7	4 1/2	5	5	2 1/2	1 1/2	4 1/2-6 1/4 AA-B
6280 22/8 heel	9	4 1/2	5	4	2 1/2	1 1/2	3-9 AA-B
6279 18/8 heel	9	3	5	4	2 1/2	1 1/2	5 1/4-7 AA-A
604 18/8 heel	7	4 1/2	3	2	2 1/2	1	3-9 AA-B
46 6/8 heel	9	5	3	4 1/2	3	1	4-8 1/4 AA-C
627 18/8 heel	9	4 1/2	3 1/2	4 1/2	2 1/2	1	3-7 1/2 AA-C
628 22/8 heel	9	4 1/2	5	4	2	1	4 1/2-8 AA-A

Having described my invention, what I claim as new and desire to secure by Letters Patent of the United States is:

1. A pad box for use in applying pressure to shoe bottoms provided with a sole receiving pad and having, in combination, means for positioning the forepart of a sole at an angle relatively to the longitudinal median line of the pad, and means for positioning the rear part of the sole centrally on the pad, the said forepart positioning means being adjusted to position the sole forepart such that the sole rear part is properly disposed relatively to the forepart after the said rear part has been positioned centrally on the pad.

2. A pad box for use in applying pressure to shoe bottoms provided with a sole receiving pad and having, in combination, means for positioning the rear part of a sole centrally on the pad, and means for initially positioning the forepart of said sole such that the sole assumes a normal undistorted shape on positioning its rear part centrally on the pad.

3. A pad box for use in applying pressure to shoe bottoms provided with a sole receiving pad and having, in combination, means for positioning the rear part of a sole centrally on the pad, means for initially positioning the forepart of said sole such that the sole assumes a normal undistorted shape on positioning its rear part centrally on the pad, means for adjusting said forepart positioning means, and a graduated scale and index finger to indicate the amount of said adjustment.

4. A pad box for use in applying pressure to shoe bottoms provided with a sole receiving pad and having, in combination, means for positioning the forepart of a sole in a predetermined position on the pad comprising an end gage for positioning the toe end of the sole and a side

gage for engaging the edge face of the sole at one side thereof, and means for moving and holding the sole against said side gage.

5. A pad box for use in applying pressure to shoe bottoms provided with a sole receiving pad, means for positioning the forepart of a sole comprising an end gage for positioning the toe end of the sole and a side gage for positioning the forepart of the sole widthwise of the pad, a longitudinally movable slide for supporting said end gage, and cam means operative upon forward movement of said slide to operate said side gage.

6. A pad box for use in applying pressure to shoe bottoms provided with a sole receiving pad, means for positioning the forepart of a sole comprising an end gage for positioning the toe end of the sole and a side gage for determining the widthwise position of the sole on the pad, a longitudinally movable slide for supporting said end gage, cam means operative upon forward movement of said slide to move said side gage into its operative position, and means for moving the sole widthwise against said side gage.

7. A pad box for use in applying pressure to shoe bottoms provided with a sole receiving pad, means for positioning the forepart of a sole comprising an end gage for positioning the toe end of the sole and a side gage for positioning the forepart of the sole widthwise of the pad, a longitudinally movable slide for supporting said end gage, cam means operative upon forward movement of said slide to operate said side gage, and means for adjusting said end gage relatively to said slide.

8. A pad box for use in applying pressure to shoe bottoms provided with a sole receiving pad, means for positioning the forepart of a sole comprising an end gage for positioning the toe end of the sole and a side gage for positioning the forepart of the sole widthwise of the pad, a longitudinally movable slide for supporting said end gage, cam means operative upon forward movement of said slide to operate said side gage, and means for adjusting said cam means relatively to said slide.

9. A pad box for use in applying pressure to shoe bottoms provided with a sole receiving pad, means for positioning the forepart of a sole comprising an end gage for positioning the toe end of the sole and a side gage for positioning the forepart of the sole widthwise of the pad, movable supporting means for said end gage, movable supporting means for said side gage actuated upon movement of said end gage supporting means, and means for adjusting said side gage relatively to its supporting means.

10. A pad box for use in applying pressure to shoe bottoms provided with a sole receiving pad, means for positioning the forepart of a sole comprising an end gage for positioning the toe end of the sole and a side gage for positioning the forepart of the sole widthwise of the pad, a slide for supporting said end gage, movable supporting means for said side gage, cam means operative upon movement of said slide to actuate said side gage supporting means, means for adjusting said side gage relatively to its supporting means, and means for adjusting said cam means to vary the sole gaging position of said side gage.

11. A pad box for use in applying pressure to shoe bottoms provided with a sole receiving pad, means for positioning the forepart of a sole comprising a toe end gage and a side gage, a slide for supporting said toe end gage, a carrier

for said slide, a support for said side gage, said side gage support being pivotally secured to said slide support, a cam plate secured on said slide, a slot in said cam plate inclined relatively to the direction of movement of said slide, and a member on said side gage support extending into said slot for the purpose of imparting inward swinging movement to said side gage support upon movement of said slide toward the sole.

12. A pad box for use in applying pressure to shoe bottoms provided with a sole receiving pad, means for positioning the forepart of a sole comprising a toe end gage and a side gage, a support for said toe end gage movable toward and from the sole, a carrier for said movable support adjustable widthwise of the shoe in a curved path in accordance with the swing of the forepart of the sole, and a support for said side gage secured to said guiding member and actuated upon movement of said toe end gage lengthwise of the sole.

13. A pad box for use in applying pressure to shoe bottoms provided with a sole receiving pad, means for positioning the forepart of the sole, a support for said positioning means adjustable about a center located in the sole surface, and means for adjusting the position of said center.

14. A pad box for use in applying pressure to shoe bottoms provided with a sole receiving pad, means for positioning the forepart of a sole, a support for said positioning means adjustable along a curved guiding member, and means for adjusting the position of said guiding member.

15. A pad box for use in applying pressure to shoe bottoms provided with a sole receiving pad, means for positioning the forepart of a sole, a support for said positioning means arranged for adjustment about a center located approximately at the intersection of the longitudinal median line of the forepart of the sole with the longitudinal median line of the rear part of the sole, and means for varying the position of said center.

16. A pad box for use in applying pressure to shoe bottoms provided with a sole receiving pad, means for positioning the forepart of a sole, a support for said positioning means arranged for adjustment along a guiding member curved about a center located approximately at the intersection of the longitudinal median line of the forepart of the sole with the longitudinal median line of the rear part of the sole, and means for varying the position of said guiding member in accordance with variations in the location of said intersection for operation upon soles of various sizes and styles.

17. A pad box for use in applying pressure to shoe bottoms provided with a sole receiving pad, means for positioning the forepart of a sole, a support for said positioning means arranged for adjustment widthwise of said pad and along a curved guiding member, a scale on said guiding member to indicate the amount of said adjustment, means for varying the position of said guiding member, and a scale and index finger to indicate the amount of variation of the position of said guiding member.

18. A pad box for use in applying pressure to shoe bottoms provided with a sole receiving pad, means for positioning the forepart of a sole comprising a toe end gage and a side gage, a support for said toe end gage movable toward and from the sole to move said toe end gage into and out of operative position, cam means for actuating said side gage upon movement of said support, means for adjusting said cam means relative

tively to said support to vary the shoe gaging position of said side gage, a scale for indicating the amount of said relative adjustment, a carrier for said toe end gage support arranged for adjustment about a center located approximately at the intersection of the longitudinal median line of the forepart of the sole with the longitudinal median line of the rear part of the sole, and a scale for indicating the amount of adjustment of said carrier.

19. A pad box for use in applying pressure to shoe bottoms provided with a sole receiving pad, means for positioning the forepart of a sole comprising a toe end gage and a side gage, a support for said toe end gage movable toward and from the sole on the pad to move said toe end gage into and out of operative position, cam means for actuating said side gage upon movement of said support, means for adjusting said cam relatively to said support to vary the sole gaging position of said side gage, a scale for indicating the amount of said relative adjustment, a carrier for said toe end gage support arranged for adjustment along a guiding member curved about a center located approximately at the intersection of the longitudinal median line of the forepart of the sole with the longitudinal median line of the rear part of the sole, a scale on said guiding member for indicating the amount of relative adjustment of said carrier, means for adjusting said guiding member, and a scale and index finger to indicate the amount of adjustment of said guiding member.

20. A pad box for use in applying pressure to shoe bottoms provided with a sole receiving pad, means for positioning the forepart of a sole comprising a toe end gage and a side gage, cam means operative upon upward movement of said toe end gage to operate said side gage, and means for moving the sole widthwise against the side gage.

21. A pad box for use in applying pressure to shoe bottoms provided with a sole receiving pad, means for positioning the forepart of a sole comprising an end gage for positioning the toe end of the sole and a side gage for positioning the forepart of the sole widthwise, a longitudinally movable slide for supporting said end gage, cam means operative upon forward movement of said slide to operate said side gage, means for adjusting said cam means relatively to said slide, and means for moving the sole widthwise against said side gage.

22. A pad box for use in applying pressure to shoe bottoms provided with a sole receiving pad, means for positioning the forepart of a sole comprising a toe end gage and a side gage, movable supporting means for said toe end gage, movable supporting means for said side gage actuated upon movement of said toe end gage supporting means, means for adjusting said side gage relatively to its supporting means, and means for moving the sole widthwise against said side gage.

23. A pad box for use in applying pressure to shoe bottoms provided with a sole receiving pad, means for positioning the forepart of a sole comprising a toe end gage and a side gage, movable supporting means for said toe end gage, movable supporting means for said side gage, cam means operative upon movement of said toe end gage supporting means to actuate said side gage supporting means, means for adjusting said cam means to vary the sole gaging position of said side gage, and means for removing the sole widthwise against said side gage.

24. A pad box for use in applying pressure to shoe bottoms provided with a sole receiving pad, means for positioning the forepart of a sole comprising a toe end gage and a side gage, a movable support for said toe end gage, a carrier for said movable support adjustable widthwise of the shoe in a curved path in accordance with the swing of the forepart of the sole, a support for said side gage secured to said carrier and actuated upon movement of said toe end gage toward the shoe, and means for moving the sole widthwise against said side gage.

25. A pad box for use in applying pressure to shoe bottoms provided with a sole receiving pad, means for positioning the forepart of a sole comprising a toe end gage and a side gage, a carrier for said sole positioning means, a guiding member curved about a center located approximately at the intersection of the longitudinal line of the forepart of the sole with a longitudinal line of the rear part of the sole, said carrier being movable along said guiding member, means for varying the position of said guiding member in accordance with variations of the swing of the forepart of the sole, and means for moving the sole widthwise against said side gage.

26. A pad box for use in applying pressure to shoe bottoms provided with a sole receiving pad, means for positioning the forepart of a sole in accordance with the swing of the forepart of said sole, and breast line gages for positioning the rear part of the sole centrally on the pad.

27. A pad box for use in applying pressure to shoe bottoms provided with a sole receiving pad, means for positioning the forepart of a sole in accordance with the swing of the forepart of said sole, and means engaging opposite sides of the rear part of said sole for positioning the rear part of said sole centrally on the pad.

28. A pad box for use in applying pressure to shoe bottoms provided with a sole receiving pad, means for positioning the forepart of a sole in accordance with the swing of the forepart of the sole, and means for positioning the rear part of the sole comprising gages for engaging opposite sides of the rear part of the sole constructed and arranged to move equally and oppositely.

29. A pad box for use in applying pressure to shoe bottoms provided with a sole receiving pad, means for positioning the forepart of a sole comprising an end gage for positioning the toe end of the sole and a side gage for positioning the forepart of the sole widthwise, and means for positioning the rear part of the sole comprising gages engaging the opposite sides of the sole substantially in the vicinity of the heel breast line, said gages being constructed and arranged to move simultaneously and uniformly in opposite directions so as to position the rear part of the sole centrally on the pad.

30. A pad box for use in applying pressure to shoe bottoms provided with a sole receiving pad, means for positioning the forepart of a sole comprising an end gage for positioning the toe end of the sole and a side gage for determining the widthwise position of the sole, a longitudinally movable slide for supporting said end gage, cam means operative upon forward movement of said slide to move said side gage into its operative position, means for moving the forepart of the sole widthwise against said side gage, and means for positioning the rear part of the sole comprising gages engaging the opposite sides of the sole substantially in the vicinity of the heel breast line, the said gages being constructed and arranged to

move simultaneously and uniformly in opposite directions so as to position the rear part of the sole centrally on the pad.

31. A pad box for use in applying pressure to shoe bottoms provided with a sole receiving pad, means for positioning the forepart of a sole comprising an end gage for positioning the toe end of the sole and a side gage for positioning the forepart of the sole widthwise, movable supporting means for said end gage, movable supporting means for said side gage, cam means operative upon movement of said end gage supporting means to actuate said side gage supporting means, means for adjusting said side gage relatively to its supporting means, means for adjusting said cam means to vary the sole gaging position of said side gage, and means for positioning the rear part of the sole centrally of the pad comprising gages for engaging opposite sides of the rear part of the sole substantially at the heel breast line thereof, the gages being constructed and arranged to move simultaneously and uniformly in opposite directions.

32. A pad box for use in applying pressure to shoe bottoms provided with a sole receiving pad, means for positioning the forepart of a sole, a carrier for said positioning means adjustable along a curved guiding member, means for adjusting the position of said guiding member, and means for positioning the rear part of the sole centrally on the pad.

33. A pad box for use in applying pressure to shoe bottoms provided with a sole receiving pad, means for positioning the forepart of a sole, a carrier for said positioning means, a guiding member for said carrier curved about a center located approximately at the intersection of the longitudinally median line of the forepart of the sole with the longitudinally median line of the rear part of the sole, means for varying the position of said guiding member in accordance with variations in the location of said intersection, and means for positioning the rear part of the sole centrally on the pad.

34. A pad box for use in applying pressure to shoe bottoms provided with a sole receiving pad, means for positioning the forepart of a sole comprising a toe end gage and a side gage, cam means operative upon forward movement of said toe end gage to operate said side gage, means for moving the forepart of the sole widthwise against said side gage, and means for positioning the rear part of the sole centrally on the pad.

35. A pad box for use in applying pressure to shoe bottoms provided with a sole receiving pad, means for positioning the forepart of a sole comprising a toe end gage and a side gage, cam means operative upon forward movement of said toe end gage to operate said side gage, means for moving the forepart of the sole widthwise against said side gage, means for positioning the rear part of the sole centrally on the pad, and common actuating means for all said gages constructed and arranged to initiate the operation of the said means for positioning the forepart of the sole before initiation of the operation of said means for positioning the rear part of the sole.

36. A pad box for use in applying pressure to shoe bottoms provided with a sole receiving pad, means for positioning the forepart of a sole comprising a toe end gage and a side gage, cam means operative upon forward movement of said toe end gage to operate said side gage, means for moving the forepart of the sole widthwise against said side gage, means for positioning the rear

part of the sole centrally on the pad, and common actuating means for all said gages, including a lost motion, constructed and arranged to initiate the operation of the said means for positioning the forepart of the sole before initiation of the operation of said means for positioning the rear part of the sole.

37. A pad box for use in applying pressure to shoe bottoms provided with a sole receiving pad, means for positioning the forepart of a sole in accordance with the swing of the forepart of said sole, means for positioning the rear part of the sole centrally on the pad, and means for positioning the toe end and the heel end of a shoe in accordance with the position of the sole.

38. A pad box for use in applying pressure to shoe bottoms provided with a sole receiving pad, means for positioning the forepart of a sole in accordance with the lateral swing of the sole, said means comprising a toe end gage and a side gage, means for positioning the forepart of a shoe associated with said toe end gage, means for positioning the rear part of said sole centrally on the pad, and means for positioning the rear end of said shoe properly with respect to said sole.

39. A pad box for use in applying pressure to shoe bottoms provided with a sole receiving pad, means for positioning the forepart of a sole comprising a toe end gage and a side gage for locating the forepart of a sole in accordance with the lateral swing of the sole, means for positioning the rear part of the sole centrally on the pad comprising two gages engaging opposite sides of the sole substantially at the heel breast line, said rear part gages being connected by arms of equal length to a toggle for the purpose of moving said gages equal amounts in opposite directions.

40. A pad box for use in applying pressure to shoe bottoms provided with a sole receiving pad, means for positioning the forepart of a sole in accordance with its lateral swing, said means comprising a toe end gage and a side gage, means for positioning the forepart of a shoe associated with said toe end gage, means for positioning the rear part of the sole centrally of the pad, means for positioning the rear end of said shoe centrally of the sole, and means for maintaining a fixed relation between said means for positioning the rear part of the sole and said means for positioning the rear part of the shoe.

41. A pad box for use in applying pressure to shoe bottoms provided with a sole receiving pad, means for positioning the forepart of a sole in accordance with its lateral swing, means for locating the forepart of a shoe in accordance with the position of the forepart of said sole, means for positioning the rear part of said sole centrally of the pad, means for positioning the rear part of said shoe centrally of the sole, and common actuating means for operating both said means for positioning the rear part of said sole and said means for positioning the rear part of said shoe.

42. A pad box for use in applying pressure to shoe bottoms provided with a sole receiving pad, means for positioning the forepart of a sole in accordance with the lateral swing of the sole, means for positioning the forepart of a shoe in accordance with the position of said sole, means for positioning the rear part of said sole centrally on the pad comprising two gages engaging opposite sides of the sole substantially at the heel breast line thereof, means for positioning the rear part of said shoe centrally on the pad, and means

for adjusting said means for positioning the rear part of said shoe relatively to said gages for positioning the rear part of said sole.

43. A pad box for use in applying pressure to shoe bottoms provided with a sole receiving pad, means for positioning the forepart of a sole in accordance with the lateral swing of the sole, means for positioning the forepart of a shoe in accordance with the position of said sole, means for positioning the rear part of said sole cen-

trally on the pad comprising two gages engaging opposite sides of the sole substantially at the heel breast line thereof, means for positioning the rear part of said shoe centrally on the pad, means for adjusting said means for positioning the rear part of said shoe relatively to said gages for positioning the rear part of said sole, and a scale for indicating the amount of said relative adjustment.

CORWIN W. BAKER.

CERTIFICATE OF CORRECTION.

Patent No. 2,239,805.

April 29, 1941.

CORWIN W. BAKER.

It is hereby certified that error appears in the printed specification of the above numbered patent requiring correction as follows: Page 1, first column, line 23, for "wtih" read --with--; and second column, line 35, for the serial number "209,324" read --290,324--; page 2, first column, line 10, for "Fig." read --Figs.--; page 3, second column, line 43, for the word "as" read --at--; page 4, first column, line 12, for "steam" read --stem--; line 21, before the reference numeral "262" insert --stop--; page 6, first column, line 38, claim 20, for "upward" read --forward--; and that the said Letters Patent should be read with this correction therein that the same may conform to the record of the case in the Patent Office.

Signed and sealed this 24th day of June, A. D. 1941.

Henry Van Arsdale,
(Seal) Acting Commissioner of Patents.
